FLYING SOLAR THERMIC TOY AIRSHIP
Bonnie Smith, Jr., Box 230, Warren, Ark., now by change
of name Bonnie Smith, Jr.
Filed Apr. 11, 1960, Ser. No. 21,280
8 Claims. (Cl. 46—89)

Summary

This invention relates to a solarthermically powered toy airship of novel attractive configuration. Several such airships are shown in the attached drawings and all comprise basically a micro-thin plastic or microfilm air envelope, the upper portion of which is transparent and through which passes the rays of the sun and the lower internal portion of which forms a solar heat concentrating reflector of exceedingly small weight. Mounted internal of the air bag or envelope and in the focal axis or point of concentration of the heat concentrating reflector is a grid which is heated by the concentrated solar rays from the reflector. This grid then heats and expands the air gases internal of the air envelope causing the airship to rise and move as a solar powered vehicle.

In obtaining best results an airship of this kind is fabricated of a light film material and the diameter of the air envelope is at least two or more feet so that sufficient buoyancy is obtained by heat expansion of the air gases inside the envelope by solar means.

Solarthermically lifted and propelled toy airships are believed new to the toy field. They fly best during clear weather such as in the spring and summer season or in regions where sunshine prevails the year through.

This kind of toy may be released as a free flying craft having the name and address of the owner on it or it may be tethered for amusement purposes by a thread of sufficient length and small weight.

Due to its simplicity the toy can be produced in many attractive shapes and colors at a very low cost. Some of the preferred shapes and element arrangements are shown in the attached drawings. For purposes of advertising, the flying solar toy may be produced in the shape and color of the product advertised.

The solarthermic lift and propulsion means in combination with toys and model airships is rather basic and is sufficient to be used to power almost any kind of weight deficient balloon or airship.

It is one object of the invention to provide a toy airship which is lifted by the action of solar energy from the sun.

Another object of the invention is to provide a toy airship which is propelled by the action of solar energy from the sun.

Another object of the invention is the provision of a simple low cost means of solarthermic propulsion in combination with model craft.

Another object of the invention is the provision of an inexpensive variety of sun toys.

Another object of the invention is the provision of sun powered flying means of advertising commercial products.

Still another object of the invention is the provision of flying toys which operate by means previously unknown in the toy field.

Still another object of this invention is the provision of a solar toy of noticeable size which is of such low cost as to be expendable like a bubble.

2

Still other novel and attractive objects and advantages of the invention will be recognized by persons skilled in the production of inflatable toys.

An example of the solarthermic toy airship will be understood from the description with accompanying drawings in which:

FIG. 1 is a front sectional view showing internal elements of the solarthermic toy airship.

FIG. 2 is a side elevational view of the solarthermic toy airship showing internal elements.

FIG. 3 is a sectional side elevational view of a flying toy Solar Saucer Ship showing internal elements and a hot air propulsion device.

FIG. 4 is a perspective view of a toy Saturn Ship showing internal elements.

FIG. 5 is a perspective view of a solarthermically lifted toy Earth Ship.

FIG. 6 is a perspective view of a solarthermic toy Moon Ship showing internal elements.

FIG. 7 is a perspective view of a toy Flying Sun Pot showing internal elements.

FIG. 8 is a perspective view of a ring shaped toy Flying Space Station showing internal elements.

FIG. 9 is a top plan view of solar powered inflatable toy Space Craft.

FIG. 10 is a side elevational view of the toy shown in drawing FIG. 9.

Flying Solarthermic Toy Airship

30 Referring to FIGURES 1, 2, 3 . . . of the drawings, it will be clear that the upper portion of all the light weight film material airships is transparent to the rays of the sun and that sun heat enters through the transparent wall 1 of air envelope 1a of the toy, strikes the solar 35 concentrating reflector 2 which due to its shape reflects and concentrates the rays into a smaller area on grid 3 which heats and expands air surrounding it inside air envelope 1, 1a of the toy airship; member 6 is an air inlet for inflation of envelope 1, 1a. As this air expands 40 due to concentration of solar heat inside the envelope 1, 1a, the airship becomes more rigidly inflated and begins rising. The solar airship shown in FIG. 2 has a jet tail-pipe 4 for the escape of excessive heat expanded internal air gases. This escape of hot air gases gives the airship 45 forward thrust. As will be noted the airship shown in FIG. 2 has an adjustable rudder fin 5 for setting the degree of turn of the toy airship. Rotating action of the airships shown in FIGS. 3, 4, 5, 6 and 7 may be had by the manufacturer applying any suitable well known means for their 50 rotation in flight.

The concentrating reflector or mirror 2 may be formed by applying any highly reflecting metallic material upon the internal wall of the air envelope, or using thin light weight material prepared so that one side is reflective to light. A thin curved mirror shaped from highly reflective tinfoil or the like may also be fitted inside the lower portion of the air envelope 1, 1a with a heat absorbing and radiating grid 3 mounted in the focal axis of said mirror. The grid 3 is preferably shaped from weight 55 deficient metallic screening or thin perforated or expanded metal sheeting which has been carbon blacked so that it absorbs and radiates heat at a higher rate. Soot may also be used for blacking the grid 3. Where expanded or perforated metal sheeting is used as the grid, a sheet thickness 60 of one thousandth inch or less is of sufficiently small weight and will function properly.

With reference to the drawings, it will be noted that the spherical toy airships FIGS. 4, 5, 6 and 7 each use the same kind of internal elements but that their outside design differs.

Referring more specifically to the flying toy Solar Saucer Ship FIG. 3, it will be seen that this toy airship comprises a disk shaped inflatable air envelope 1, 1a, the upper half of which is transparent and through which passes sun rays shown as broken lines with arrowhead pointers. These sun rays are reflected and concentrated by reflecting mirror 2 which covers the lower internal half of the airship. Located in the focal point of reflector 2 is a second mirror-like reflector 7 which acts as a beam reverser thereby reflecting the beam from concentrating reflector 2 upon sintered air expansion chamber 8 which serves two purposes. Chamber 8 is caused to become very hot due to the concentrated rays from the sun upon it. The outside of chamber 8 heats and expands air internal of air envelop 1, 1a making the toy airship buoyant. External air feeding into air intake 9 travels into the air expansion chamber 8 through the pressure nozzle arrangement inside air intake pipe 9. Upon entering heated chamber 8 the air gases are rapidly expanded to several times the original air volume and forced out through tail-pipe 19. In tail-pipe 10 the hot expanded air gases mix with cool air giving considerable thrust to the toy airship. Direction of air flow is shown by arrowhead pointers. Since beam reversing mirror 7 tends to heat up considerably it should have a thin metallic reflecting surface such as foil or the like and be constructed or bonded so that heat does not affect it or cause air bubbling under the mirror-like surface. In FIG. 3 the air expansion propulsion chamber 8 and associated parts are shown larger in respect to the air envelope 1, 1a than they would normally be in actuality.

The toy Moon Ship FIG. 6 and the toy Sun Pot FIG. 7 have eyelets 11 of small weight evenly spaced around the outside of their lower portions for the purpose of tilting the spheres by the use of exceedingly small amounts of weight.

The ring-shaped toy flying Space Station FIG. 8 is a solar heat lifted inflatable envelope, the upper portion 1 of which is transparent to the rays of the sun. The inside of lower portion 1a comprises a reflecting mirror 2 of parabolic cross-section. Air internal of envelope 1, 1a is heated and expanded by grid 3 located in the focal axis of reflector 2. Excessive hot air escapes from the envelope 1, 1a and the hot air remaining therein causes the inflatable envelope to rise and float with the breeze.

A flying toy Space Craft such as shown in FIG. 9 and FIG. 10 operates as follows—sun rays pass through the upper transparent portion 1 of the inflatable envelope 1, 1a and strike the reflecting mirror 2 which concentrates them upon beam reversing mirror 7, from mirror 7 the rays travel to a sintered air heating and expansion chamber 8 which heats and expands air gases inside the inflatable air envelop 1, 1a making the inflatable envelope buoyant and at the same time expanding at a higher rate a continuous flow of air gases passing through solar heated air expansion chamber 8. This expanded air stream gives thrust by reaction to the flying toy.

A sun powered drifting toy airship of lesser efficiency can be constructed by elimination of focusing internal reflector 2 and grid 3 and covering the area previously covered by reflector 2 with a sintered black coating which will absorb sun heat and expand air gases inside envelope 1, 1a.

This description is intended to be illustrative and does not constitute a limitation upon the scope of this invention beyond the scope of the appended claims.

What I believe to be novel and useful and wish to secure by Letters Patent is:

1. A solar heat powered flying toy comprising an inflatable air envelope, an upper portion of which is transparent and through which passes the rays of the sun, a

5 lower internal portion of said air envelope comprising a solar concentrating mirror with said mirror focusing said rays upon an air heating grid located internal of said air envelope, means holding said grid in the focus of said concentrating mirror and pressure operated means for the escape of excessive hot expanded air from said inflatable envelope.

10 2. A solar heat operated toy airship comprising an inflatable air envelope, an upper portion of said envelope being transparent and through which passes the rays of the sun, a lower internal portion of said envelope comprising a solar concentrating reflector, an air heating grid located in the focus of said reflector internal of said inflatable envelope and pressure operated means in the wall of said envelope for the spill-out of excessively expanded hot air gases.

15 3. A solarthermic flying toy space ship comprising an inflatable envelope, an upper portion of which is transparent and through which passes the rays of the sun, a lower internal portion of said envelope comprising a heat concentrating reflector, a beam reversing reflector located in the focal beam of the first reflector, a sintered air heating expansion chamber located in the focal beam of the reversing reflector with said expansion chamber for air having connected thereto both inlet and outlet tubing for the flow of air gases, with the upper wall of said air expansion chamber heating the gases internal of said inflatable envelope.

20 4. A solar heat operated toy airship comprising a ring shaped inflatable air envelope, the upper portion of which is transparent and through which passes the rays of the sun, the lower internal portion of said envelope comprising a solar concentrating mirror-like reflector of parabolic cross-section, a heat absorbing radiating grid mounted in the focal axis of said concentrating reflector, with the hot air capacity of said envelope being sufficient to cause the airship to rise and float.

25 5. A solar heat operated toy airship of inflatable spherical configuration, an upper portion of which is transparent and through which passes the rays of the sun, the lower internal portion of said inflatable airship forming a solar heat concentrating mirror, an air heating grid mounted in the focal point of said mirror, with the lower external portion of said inflatable toy being colored attractively.

30 6. A solar heat powered flying toy saucer ship comprising a disk shaped inflatable air envelope, an upper portion of which is transparent and through which passes the rays of the sun, a reflective lower internal portion of said inflatable envelope forming a first solar heat concentrating mirror, a second solar mirror located in the focal beam of said first mirror reversing the direction of said solar beam, a sintered air expansion chamber located in the focal point of said second concentrating mirror and internal of said air envelope, a unidirectional air inlet means leading to said air expansion chamber and a jet exhaust outlet connected to said chamber.

35 7. A solar heat operated toy airship comprising a spherical inflatable air envelope the upper portion of which is transparent and through which passes the rays of the sun, the lower internal portion of said air envelope comprising a heat concentrating mirror, a heat radiating grid mounted in the focal point of said mirror heating and expanding the air gases internal of said envelope with the outer surface of said airship being attractively decorated.

40 8. A solar heat powered toy airship comprising an air envelope, an upper portion of which is transparent and through which passes the rays of the sun, a lower internal portion of said air envelope forming a solar concentrating mirror with said mirror focusing said rays upon an air heating grid located internal of said air envelope, means holding said grid in the focal axis of said concentrating mirror and pressure operated means for the directional

escape of excesses of expanded air gases, suitable means for the inflation of said air envelope and adjustable control surface fins attached to said toy airship.
